UNITED STATES PATENT OFFICE.

JOSEPH TERREL, OF ROYAL CENTRE, INDIANA.

IMPROVEMENT IN LIFTING-JACKS.

Specification forming part of Letters Patent No. 123,593, dated February 13, 1872.

To whom it may concern:

Be it known that I, JOSEPH TERREL, of Royal Centre, in the county of Cass and State of Indiana, have invented a new and Improved Machine for Raising Wagons and other heavy articles, called a Wagon-Jack; and I do hereby declare that the following is a full and exact description, reference being had to the annexed drawing and to the letters and numbers of reference thereon.

This invention relates to improvement in lifting-jacks; and it has for its object the production of a device for slightly elevating heavy bodies by hand-power—a device simple in construction, handy, effectual when used, and free from the objections of liability to totter or yield to lateral pressure.

Referring to the accompanying drawing, A represents the base, which is preferably made in a triangular shape, and of a size sufficient to insure the required strength and firmness. The lever-support B rests in a mortise in the wide end of the base A, and projects upward at a suitable inclination to be properly supported by the brace C. The upper end of the sup-

port B is slotted to receive the lever E, as shown, and pierced for the fulcrum-pin 12, on which the lever rests. The lever E is preferably made in the form shown, the short arm scalloped to secure a firm hold on the body to be elevated, and the long arm tapering, smoothed for the hand, and adjustable by means of a pin, and a perforated standard, D, firmly secured in a mortise in the narrow end of the bar A, all as represented.

I claim as my invention—

A lifting-jack, consisting of the triangular base A, lever-support B, and brace C, both firmly secured in the base A, and the support B being inclined and slotted, the lever E and the standard D provided with holes and pin to secure the end of the lever, and firmly mortised in the narrow end of the bar A, all constructed and arranged substantially as and for the purposes set forth.

JOSEPH TERREL.
